UNITED STATES PATENT OFFICE.

EDGAR QUICK, OF COLUMBUS, GEORGIA.

PUMP OR FILLING DEVICE.

SPECIFICATION forming part of Letters Patent No. 718,382, dated January 13, 1903.

Application filed April 30, 1902. Serial No. 105,341. (No model.)

To all whom it may concern:

Be it known that I, EDGAR QUICK, a citizen of the United States, residing at Columbus, in the county of Muscogee and State of Georgia, have invented new and useful Improvements in Pumps or Filling Devices, of which the following is a specification.

My invention relates to new and useful improvements in pumps or filling devices for sight-feed lubricators; and its object is to provide a simple device by means of which oil can at any temperature be placed within the lubricator without removing the cap thereof. Heretofore it has been found necessary to maintain oil at a certain temperature in order to keep it in a limpid state to permit it to be poured into the filler-hole of the receptacle of the lubricator. Unless the lubricant was sufficiently thin or the lubricator perfectly steady the oil would flow over the sides of said lubricator and become not only wasted, but also soil the machinery. Moreover, by the slow process of pouring the expenditure of a considerable amount of time is required to fill the lubricator.

The objects of my invention are to overcome the above difficulties and to provide a pump attachment of novel construction adapted to quickly transfer the contents of an oil-can to the lubricator, to so construct the pump as to force oil of any temperature or thickness into the lubricator, and to provide means for filtering the lubricant prior to its discharge into the receptacle of the lubricator.

With the above and other objects in view the invention consists in the novel construction and combination of parts hereinafter more fully described and claimed, and illustrated in the accompanying drawings, showing the preferred form of my invention, and in which—

Figure 1 is a central longitudinal section through a filling-pump attached to a lubricator. Fig. 2 is a similar view of a modified form of pump. Fig. 3 is an elevation of a lubricator, showing the various positions in which the pumps may be arranged in relation thereto.

Referring to the figures by numerals of reference, 1 is a lubricator having an exter-

nally-threaded nipple 2 extending therefrom and engaging a cylindrical valve-casing 3, having a contracted passage 4 therein, at one end of which is a tapered valve-seat 5, while at the end nearest the nipple 2 is a seat 6 for a ball-valve 7. This ball is retained in position within the casing 3 by means of a screen-strainer 8, secured within said casing between the nipple 2 and a shoulder 9, formed in the casing.

The outer end of the casing 3 is threaded and engages a cylinder 10 of suitable size, having a head 11 detachably fitted in its free end. This head is provided with a centrally-located threaded aperture 12, within which is slidably mounted a rod 13, having a ring 14 or other means at its outer end whereby it can be readily grasped. The inner end of the rod 13 is provided with a cut-off valve 15, adapted when pressed inward to bear upon the seat 5, and it can be locked or held in such position when the pump is not in use by turning threads 16, formed on the rod 13, into engagement with the threaded aperture 12. A suitable piston 17 is secured to rod 13 in rear of the valve 15.

A hollow arm 18 extends from the casing 3 at a point adjacent to valve-seat 5 and is provided with a shoulder 19 at its inner end, against which is fitted a screen-strainer 20. The outer end of the arm 18 receives the end of a suction-pipe 21, having a seat 22 at its inner end for a ball-valve 23.

When it is desired to fill the lubricator 1, the suction-pipe 21 is placed in a can 24, containing oil. The rod 13 is then turned until its threads 16 are disengaged from the head 11, and the piston 17 is drawn outward. This action will close valve 7 and open valve 23, and the oil will be drawn up through pipe 21 and into cylinder 10. When the motion of the piston is reversed, the valve 23 is closed and valve 7 opened, and the oil in the cylinder is forced through the nipple 2 and into the lubricator.

It will be understood that the strainers 20 and 8 prevent the admission to the lubricator of any impurities which may be contained within the oil.

By assembling the parts in the manner herein shown and described they can be readily

- detached for cleaning purposes. If desired, the pump may be placed parallel with the side of the lubricator, as shown in Fig. 2, and in such case the construction will be the same as that hereinbefore described, with the exception of the nipple 25 and suction-pipe 26, which are elbowed, as shown. Moreover, the pump may be secured not only in a horizontal or a vertical position at the lower end of the lubricator, but can also be arranged at an incline at the upper end, as shown in Fig. 3, in which I have illustrated the various positions of the pump in relation to the lubricator.
- 15 In the foregoing description I have shown the preferred form of my invention; but I do not limit myself thereto, as I am aware that modifications may be made therein without departing from the spirit or sacrificing any of 20 the advantages of the invention, and I therefore reserve the right to make all such changes and alterations as may fairly fall within the scope of my invention.
- Having thus fully described the invention, 25 what is claimed as new is—
1. The combination with a lubricator, of a valve-casing secured thereto, and provided with valve-seats, a valve located in one of the seats, a cylinder having connection with the 30 valve-casing, a rod mounted within the cylinder, a piston secured to the rod, and a cut-off

valve carried by the rod, and adapted to occupy the other valve-seat.

2. The combination with a lubricator, of a valve-casing secured thereto, and provided 35 with valve-seats, a valve located in one of the seats, a suction-pipe connected with the casing, a cylinder having connection with the valve-casing, a rod mounted within the cylinder, a piston secured to the rod, a cut-off valve 40 carried by the rod, and adapted to occupy the other valve-seat, and means for retaining the cut-off valve seated.

3. The combination with a lubricator having a nipple extending therefrom, of a valve-casing secured thereto, a valve and a strainer in said casing, a cylinder secured to the casing, a piston therein, a threaded head to the cylinder, a threaded rod to the piston and extending through the head, a cut-off valve 45 upon the rod adapted to be held upon a seat in the casing when the threads of the rod engage the cylinder-head, a suction-pipe opening into the casing and cylinder, and a valve and a strainer in said pipe.

In testimony whereof I affix my signature in presence of two witnesses.

EDGAR QUICK.
